CAP REMOVER

Louis Sheldon, Chicago, Ill.

Application October 26, 1936, Serial No. 107,527

8 Claims. (Cl. 81—3.1)

This invention relates to devices for releasing caps or lids for containers such as fruit jars and is adapted for use more particularly in connection with caps which are capable of being released by being pried off.

A type of cap which nowadays enjoys considerable popularity is self-clamped to the neck of containers such as bottles, cans, jars and the like. Such caps usually have gaskets and may be held in place by vacuum in the container. The cap and container provide spaced opposed abutments or surfaces between which part of a tool is adapted to be placed for prying off the cap. Users have been advised to employ coins, knives, screw drivers and other implements and impart a twist or crowbar action to them to pry off the cap. This has proved highly unsatisfactory in all cases except those wherein the cap is so loosely applied as to provide an undependable seal. As an alternative the use of a tool akin to the old-fashioned can opener has been suggested. By this device, comprising a substantially U-shaped element with a short leg to engage under the ledge of the lid and a long leg to impinge upon the top of the lid, the end of the long leg is pressed down on the lid while the short leg is pulled upward. This is very inconvenient at best and, after a series of such operations circumferentially of the lid, it may be removed, but at the cost of one's composure and with such distortion of the lid as to render it unfit for subsequent use, which use is often desirable as when only a part of the contents of the container has been removed.

The use of such prior devices, moreover, is attendant with danger of personal injury due to the likelihood of slipping of such devices, and breakage, scratching or the like of cap, container, and knife or other tool.

Because of the lack of a better cap-prying device, considerable sales resistance to containers equipped with such caps has developed, notwithstanding their desirability from a sealing standpoint.

The objects of my invention are to provide a device free of the foregoing objections.

Bearing in mind the abovementioned and other difficulties encountered with present cap-prying devices, I have devised a structure of this character which may be produced in quantities at an extremely low manufacturing cost, without relatively moving parts, and by which a cap may be removed substantially by a single short movement without injury to the tool, without distorting the cap and without personal danger.

In accordance with the general features of my invention, there is provided a preferably arcuate elongated part one end of which is adapted to be inserted in the space between the opposed shoulders of the container and cap, and engageable with one of the shoulders while the trailing portion engages the other shoulder. Upon application of a prying force tending to rotate the arcuate part substantially in its plane, portions of said part successively more distant from said end are engaged with the adjacent shoulder, and the shoulders are thereby separated. Of course the device may be of any desired dimensions so that the maximum distance between the end and the other shoulder engaging portion will be such as to free the cap from the container.

Further objects and advantages of the invention will appear as the description proceeds.

The invention will be understood upon reference to the following description and the drawings, in which:

Figure 1 is an isometric view of one form of the invention.

Figure 2 is fragmentary rear elevation of the same in position preparatory to clockwise prying action.

Figure 3 is a plan view of the tool of Figure 2, with the cap removed.

Figure 4 is an enlarged sectional view taken substantially as indicated by the line IV—IV in Figure 1.

Figure 5 is a fragmentary sectional view taken as indicated by the line V—V in Figure 2.

Figure 6 is a reduced fragmentary sectional view taken substantially as indicated by the line VI—VI in Figure 5, the relation of the parts after the commencement of the prying action being shown in dotted lines.

Figure 7 is a view similar to Figure 5 but shows the relation of the parts corresponding to the dotted lines in Figure 6.

Figure 8 is a view similar to Figure 6 but showing another method of using the tool, and a modified cap construction.

Figure 9 is similar to Figure 7 but shows the parts in the relation indicated by the dotted lines in Figure 8.

Figure 10 is similar to Figure 9 but shows a modified cam point.

Figure 11 is a plan view of another form of the invention.

Figure 12 is a sectional view taken substantially as indicated by the line XII—XII in Figure 11.

Figure 13 is a rear elevation taken as indicated by the line XIII—XIII in Figure 11.

Figures 14 and 15 are respectively front elevational and plan views of another form of the invention.

Figures 16 and 17 are respectively front elevational and plan views of another form of the invention.

Figures 18 and 19 are plan and rear elevational views of another form of the invention.

Figure 20 shows another cam construction.

10 Figure 21 shows a modified container shoulder.

Referring now more particularly to the drawing, any suitable container is shown at 1, having a ledge or shoulder 2 and a neck 3 to which a cap 4 is adapted to be clamped or crimped in sealing 15 or other closing relation thereto. The cap and container may be of any suitable construction, shape and material. The cap may be provided with a skirt 5 in which is disposed a gasket 6 for sealing purposes.

20 The cap has an inturned rim or margin 7 serving to retain the gasket and providing a ledge or shoulder adapted to face and lie in space relation to the shoulder 2, when the cap is fixedly clamped to the container.

25 A tool embodying the principles of the invention is shown generally at 8, and comprises a sheet metal stamping formed with thumb and finger handle or press portions 9 to adapt the piece to be manually rotated and a prying cam 30 10 formed as by being struck up from a preferably central body portion 11 offset from the ends 12. The cam 10 is preferably generally U-shaped. The sides or arms 13 and 14, or either of them, extending from the bight 15, may be substantially normal to the body portion 11, and are preferably straight and flat and sufficiently thin to be readily inserted in the narrow space 16 usually found between the shoulder 2 and rim 7. This space has been found in practice to vary from about $\frac{1}{32}$ " to about $\frac{3}{32}$ ", and accordingly each arm may be made sufficiently thin, without undue sacrifice of strength, to lend itself to ready insertion in the minimum space.

35 The tool may be conveniently manipulated by 45 both right-handed and left-handed persons, when both cam arms are formed as has been described, in either of two ways. When the arm 13 is placed in the space 16 so that the free end 17 of the arm is at the right, and the arm 14 is at a lower level, as shown in Figures 2, 3, 5 5 and 6, and the tool is turned clockwise, the end 17 will engage the jar shoulder 2 and the bight 15 of the cam will slide up and along the cap rim 7, camming the cap upward until the cap is released from the neck 3. By placing the arm 13 in the space 16 with the free end 17 at the left and the arm 14 at a higher level, as seen in Figures 8 and 9, and turning the tool clockwise, the free end 17 engages the cap rim 7a in Figure 60 8 or 7 in Figure 9, camming the same upward as the bight 15 slides along the jar shoulder 2. The cap rim 7a is corrugated or otherwise roughened to interlock with the end 16. With the arm 14 in the space 16 and the free end 18 of said 65 arm 14 at the left, and the other arm 13 either below or above, the tool is turned anti-clockwise to effect a camming up of the cap either by the free end 18 or by the bight 15, as will be understood readily from the foregoing explanation.

70 The cap may be raised in stages instead of in one operation, by applying the tool at two or more spaced points along the space 16.

In order to guard against accidental slipping of the tool, the thumb or a finger of the hand 75 not applying the tool, i. e., the hand held over

the top of the container assembly to steady it, may be placed against the back 19 of the central body portion 11 and press the same toward the jar neck. The jar shoulder may be raised at its outer periphery as shown at 20 in Figure 21 to provide a guard against accidental escape of the tool, however used. For this purpose also, I may notch the free end of each arm to provide a single edge at the point as at 17, 18 or a V-edge as at 21, and I may flare the bight 15 to provide an outer edge 22. Thus, referring to Fig. 5, for example, it will be observed that the blade, from the free end portion 17 or 18 to the fulcrum 15 (Fig. 1) varies in length so that the free end portion can be positioned between the skirt of the cap and the neck of the container. A similar arrangement is made at 33 in Fig. 18 and at 21 in Fig. 10, and in other modifications as is apparent from the drawing.

20 The point, or the edge 22, as the case may be, when applied to the rim 7 or 7a, is worked into interlocked relation thereto as shown in Figures 7, 9 and 10, so that the cap rim itself retains the point or edge, as the case may be, from slipping out. In the use of the tool, as will be apparent from the foregoing, either point or the edge 22 is thus interlocked with the cap.

25 Figures 11, 12 and 13 show a form similar to that described above, differing substantially only in respect to the handle construction. Here the ends are turned back and twisted to provide the thumb and finger press portions 23. The cam is numbered as above.

30 In accordance with another form of the invention, illustrated in Figures 14 and 15, the stamping may be formed with a handle portion 24 at one end and a cam 25 at the other. The body may be flat but is preferably offset adjacent the cam, similarly to the portion 11 previously described. The cam is shown with its bight 26 40 at the end of the tool, although obviously the cam could be reversed so that its convex portion faces the handle end, or arranged in any other suitable position. A hole 24a may be provided to hook the tool to a support.

45 Another form is shown in Figures 16 and 17. This structure is similar to that in Figure 1, but spaced cam flanges 27 are provided, a longitudinal intermediate strip 28 being struck back and bent at right angles to provide a handle.

50 A tool embodying the principles of the invention may be formed of wire, as shown in Figures 18 and 19. In one form, shown generally at 29, the tool terminates in a cam 30 having a flattened free end portion 31 for fitting in a narrow space 16 and a rounded portion 32 which may be of the normal wire form in cross section and/or may be flared to provide an edge corresponding with the edge 22 of the first described form of the invention. The thumb of the hand not 60 applying the tool may be placed against the rear side of the cam and press it toward the jar neck to aid in preventing slipping of the tool as it is being rotated.

65 The free end portion 31 may be formed with a notched point 33, similar to that shown at 21, to receive the cap rim when the tool is applied in that way, providing an interlock preventing accidental disengagement as the tool is rotated.

70 Each flattened portion 13, 14, 31 may be of generally knife form, that is, with a relatively sharp outer edge, which may be pushed wedge-fashion between very closely spaced cap rim and jar shoulder portions or abutments to effect suffi- 75

cient entry of said flattened portion to enable the tool to be effectively manipulated.

In case of a cap with a skirt type of rim such as appears at 34 in Figure 20, the free end of the cam may be pointed as at 35 to bite the rim, and, if necessary, may be held by the free hand against slipping.

The handle may be in any desired relation to the cam. Preferably, however, the handle is inclined to the flattened portion or portions of the cam so that when such portion is positioned substantially horizontally, as will usually be the case because the jar will ordinarily be resting on a horizontal base, the thumb and index finger, applied to spaced parts of the handle, may assume natural positions with the thumb and finger at different elevations.

It will be appreciated that the tool is also useful to pry out flanged stoppers and can tops, where opposed surfaces, one on the container and the other on the stopper or top, furnish abutments adapted to be pried apart by the tool.

The tool does not appreciably mar the cap, so that the latter, after having been removed by the tool, may be pressed on the jar neck by hand, as is often desirable when only a portion of the contents of the jar has been removed.

With this invention the prying portions of the tool are at all times in such close proximity to each other that a large force multiplication is obtained, requiring little effort to cam the cap free of the container. The tool is equally operable by right and left handed persons.

It will be evident from the foregoing that, whether made of sheet metal, wire or other material, the tool is effective, durable, requires but a single turning movement involving so little energy that any housewife may operate it, and may be manufactured in large quantities at low cost.

40 I am aware that many changes may be made and numerous details of construction may be varied through a wide range without departing from the principles of this invention, and I therefore do not purpose limiting the patent granted hereon otherwise than necessitated by the prior art.

I claim:

1. A prying tool for container closures, said tool comprising an elongated prying part having a substantially plane end portion insertable between a container and a closure therefor after the closure is sealed on the container, and a portion arched longitudinally of and extending from an end of said plane portion and inclined transversely relative to said plane portion.

2. A prying tool comprising a lever having an end portion insertable between substantially parallel surfaces of a container and the skirt of a cap therefor after the cap is sealed on the container, said lever having a fulcrum portion slidably engageable with one of the surfaces while said end portion engages the other surface as the tool is turned, each of said portions having an edge engageable behind the skirt, when the other portion is engaged with the container surface.

3. A rotary prying tool comprising a metal body from which a flange extends transversely, an end portion of the flange being insertable between mutually facing surfaces of a container and a skirted cap therefor after the cap is sealed to the container, the transverse extent of the flange being such that when the flange is fully inserted said body adjacent the flange is disposed adjacent one of said surfaces, said flange inwardly of said end portion having a fulcrum portion

slidably engageable with one of the surfaces while the end portion engages the other surface as the tool is turned, said body having thumb and finger handle means disposed at opposite ends of the body and laterally spaced from the flange so that 5 the hand may press the back of said body to steady the tool while turning it.

4. A rotary prying tool comprising a body having a projecting part, said part comprising angularly related substantially straight arms, each of 10 which is selectively insertable between and along closely spaced mutually facing surfaces of a container and the skirt of a cap therefor after the cap is sealed to the container, said arms being joined by a fulcrum portion slidably engageable 15 with one of the surfaces while the free end of either arm selectively engages the other surface as the tool is turned, said body having a handle spaced from said arms.

5. A prying tool for container closures, said tool 20 comprising an elongated substantially flat prying blade, substantially the full length of said blade being insertable between the mutually facing peripheral surfaces of a container and a skirted closure therefor after the closure is sealed on the 25 container, said blade having a portion engageable and interlockable with the skirt surface while another portion longitudinally spaced from the first portion engages said container surface, the places of engagement being spaced apart peripherally of said surfaces when the tool is in prying position on the container, and handle means disposed to swing said blade about an axis substantially normal to the axis of the container.

6. A tool of the type described, comprising a 35 handle, a blade extending transversely from said handle, the blade having a flat portion terminating in a free end portion for entering into the space between the shoulder of a container and the rim of the skirt of a cap located on the neck 40 of and closing said container, a portion of the blade remote from said free end portion extending angularly from said flat portion to thereby provide a fulcrum for said end and flat portion of the blade when the blade is moved to pry the 45 cap from the container, said free end portion having a groove adapted to receive the rim of the cap to prevent slipping of the tool from the cap when the tool is in use.

7. A tool of the type described, comprising a 50 handle, a blade extending transversely of the handle, the blade having a flat portion terminating in a free end portion for entering into the space between the shoulder of a container and the rim of the skirt of a cap located on the neck 55 of and closing said container, a portion of the blade remote from said free end portion extending angularly from said flat portion to thereby provide a fulcrum for said end and flat portions of the blade when the blade is moved to pry the 60 cap from the container, the blade from the free end portion to said fulcrum varying in length so that the free end portion can be positioned between the skirt of the cap and the neck of the container to prevent slipping of the tool from 65 the cap when the tool is in use.

8. A prying tool for closures for cylindrically shaped containers, said tool comprising a prying part insertable between the mutually facing peripheral surfaces of a container and a skirted 70 closure therefor after the closure is sealed on the container, said part having a pointed end engageable and interlockable with said skirt while another portion of said prying part engages said container surface, the places of engagement being 75

spaced apart peripherally of said surfaces when the tool is in prying position, and handle means connected to said prying part and disposed to swing said prying part about an axis substantially normal to the axis of the container, said handle means being substantially longer than

said prying part and extending from said prying part in a direction generally normal to a radius of said container when the tool is in prying position, whereby said handle means may be readily grasped by the operator for manipulation. 5

LOUIS SHELDON.
